ATTORNEY.

UNITED STATES PATENT OFFICE

LUDWIG OBERMEIER, OF BROOKLYN, NEW YORK

HEEL ATTACHMENT

Application filed March 12, 1929. Serial No. 346,337.

My invention relates to heel attachments, and has for its particular object to provide an attachment adapted to be easily attached to a heel in such a position as to prevent the stocking or sock of the wearer from being spattered when the streets are muddy.

The device, according to my invention, is preferably made of metal and is provided with two cooperating fingers preferably formed integral with the attachment, whereby the latter is held in fixed position on the heel.

While the attachment is principally intended to be worn on ladies' shoes, it can, of course, also be worn by men.

In the annexed drawing, I have shown by way of illustration an embodiment of my invention, Fig. 1 of the drawing showing a lady's shoe with the attachment in position on the heel; Fig. 2 is a transverse section along line 2-2 in Fig. 1, Figs. 3 and 4 are transverse sections respectively along lines 3-3 and 4-4 in Fig. 2; Fig. 5 is a detail view showing the interlocking fingers, while Figs. 6, 6^a and 7 show a slight modification of the fingers.

As shown in the drawing, the attachment comprises a body part 1 formed somewhat like a horse-shoe so as to fit around the heel. The body part 1 is of curved contour, as more clearly shown in the sectional views of Figs. 3 and 4. At the inner ends of the body part 1 are formed two fingers 3 and 4 adapted to be interlocked so as to hold the body part 1 firmly in position on the heel.

The two fingers 3 and 4, which are formed preferably integral with the body part 1, may be formed as shown in Fig. 5 in which the finger 3 is shown with small apertures 5, while finger 4 is shown with a prong 6 (Fig. 2) adapted to enter any of the apertures 5 which, as shown in Fig. 5, are arranged in juxtaposition so that the interlocking position of the fingers can be adjusted according to the width of the inner face of the heel.

In Figs. 6, 6^a and 7, a modification of the inner ends of the two fingers are shown. In the latter case, the finger 3 is provided with T-shaped apertures adapted to be engaged by

a correspondingly hook-shaped member 8 on the end of the finger 4.

On the inner side of the body part 1 in the center thereof is shown a small prong 9 (Fig. 4), which, as the attachment is pushed over the heel, will slightly penetrate into the heel so as to prevent slipping of the round portion of the body part 1.

On both sides of said prong, spaced therefrom, are furthermore provided slightly projecting rubber pads 10 to prevent the heel from becoming scratched as the attachment is placed on the heel.

Preferably, the attachment is made of a metal permitting the fingers 3 and 4 to be flexed back and forth without becoming brittle, but the attachment can, of course, be made of any other suitable material, and the fingers 3 and 4 instead of being formed integral with the body part 1 can be riveted, or otherwise fastened, thereto.

In fact, I do not limit myself to the attachment as shown, as the same is capable of further modifications without constituting a departure of my invention.

I claim:

A heel attachment for the purpose described comprising a body part of U shape and semi-circular cross section, thereby defining an inner portion adapted to hug a heel and an outer portion spaced from said inner portion, a retaining prong situated upon said inner portion at the crotch of said U-shaped body part and projecting inwardly so as to penetrate said heel upon which said attachment is fixed, integral retaining fingers projecting from the ends of said inner portion adapted to cooperate with one another to fix said attachment upon said heel, and one of said fingers having a prong to penetrate said heel cooperating with said first named prong to retain said attachment upon said heel.

In testimony whereof I affix my signature.

LUDWIG OBERMEIER.
